UNITED STATES PATENT OFFICE.

EDMUND C. MORGAN, OF CHICAGO, ILLINOIS.

CUTTER-CHAIN FOR MINING-MACHINES.

1,325,028.

Specification of Letters Patent. Patented Dec. 16, 1919.

Application filed July 3, 1914. Serial No. 848,726.

To all whom it may concern:

Be it known that I, EDMUND C. MORGAN, a citizen of the United States, residing at Chicago, in the county of Cook and State of Illinois, have invented certain new and useful Improvements in Cutter-Chains for Mining-Machines, of which the following is a specification.

This invention relates to mining machines and more particularly to the construction of the cutter chain and the parts thereof, by which the cutters are held. The principal object of the invention is to provide a new and improved cutter chain mechanism for mining machines of the endless cutter type, particularly as disclosed in my application for mining machines, Serial No. 848,727, filed July 3, 1914.

More particularly it is the object of the present invention to provide improved cutter chain mechanism for mining machines of the loop chain type wherein the plane of the driving mechanism is out of the plane of the kerf cut by the cutter chain.

25 A further object of the invention is to provide guiding mechanism on the side of the chain opposite from that of the cutters and interlocking with the chain support to prevent dislocation of the cutter chain with respect to said support.

Another object of the invention is to provide a loop cutter chain with rollers running on a plate projecting from said support, a cutaway portion of the links relatively to 35 said rollers being provided to allow for considerable wear between the rollers and said projecting plate.

A further object of the invention is the provision of specially constructed bolt heads 40 coacting with guide grooves, such bolts being prevented from turning by projections from the links between the cutter links.

Other objects of the invention will appear hereinafter, the novel combinations of 45 elements and the novel features of the invention being set forth in the appended claims.

In the drawings:

Figure 1 is a view of a portion of a chain, 50 parts being shown in full and parts in section, constructed in accordance with the principles of my invention in combination with a guide and support therefor.

Fig. 2 is a side elevation of the same, 55 partly in section.

Fig. 3 is a view of the outer side of one of

the cutter blocks, with parts of the connecting links.

Fig. 4 is a sectional view on the line 4—4 of Fig. 1, and

Fig. 5 is a sectional view on the line 5—5 of Fig. 1.

In operating continuous cutter chains in mining machines it is necessary that the cutters may be removed from the cutter blocks or cutter chains, and inserted therein, as quickly as possible. It is also necessary that cutter chains of the class to which the present invention appertains be provided with a support of such nature that the cutter chain, which is movable, will not become disengaged from the support, or will not slide or fall therefrom regardless of the direction or position of the support. This is readily apparent, for in some of the cutting operations the support may be upside down and unless a suitable construction were employed the cutter chain would fall bodily therefrom.

In the present invention the numeral 8 designates generally a cutter block formed with pairs of spaced perforated lugs 9 at opposite ends thereof, and with a bit socket 10 having an enlargement 11 adjacent thereto, the socket 10 being adapted to receive a shank 12 of a bit, the tip 13 of which extends from the outer side of the cutter block at an angle thereto, forming a shoulder 14, which limits or predetermines the extent to which the shank 12 of the bit may be inserted in the socket 10. At the side of the bit, opposite the shoulder 14 and in the enlarged portion 11 a locking key 15 is inserted having a wedging face to correspond with a wedging face of the enlarged portion. 90 At the outer end the locking key is formed with a hook 16, by which it is adapted to be engaged by a tool 17, as shown in dotted outline in Fig. 1, for withdrawing or partially withdrawing the key from the socket. The inner end of the locking key 15 is pivoted or otherwise connected to a stirrup 18, and the cutter block is formed with a recess 19, in which is a projection 20 to contain the stirrup and to permit a longitudinal movement thereof. Disposed between the stirrup and the projection 20 is a spring 21, which presses the stirrup downwardly, drawing with it the locking key 15, which tends to press the shank 12 of a bit 110 in the socket against the opposite side of the socket and to hold the bit firmly in position

with its shoulder 14 against the outer end of the cutter block.

To connect the adjacent cutter blocks a pair of oppositely disposed links 22 and 23, each having projections 24, is inserted from opposite sides through the perforations of the lugs until the corresponding projections engage each other, and mounted on each pair of projections between the corresponding lugs 9, is a roller 25, which substantially fills the space between the lugs 9, and is preferably of such a diameter that the outer face is flush with the lugs 9 and the links 22 and 23, as shown in Fig. 4, with the exception of the lower side of one of the lugs 9, and one of the links 23, as clearly shown in Fig. 4.

A bolt 26 is inserted through the abutting projections of opposite link members 22 and 23, and is preferably provided with a head 27 having a projection 28 on one side of the chain and with an ordinary fastening nut and washer 29 and 30.

The chain moves upon and is held by a support 31, upon which the rollers run, with a member 32 forming a shoulder 33 against which the inside edge of the chain abuts, the support 31 extending the full width of the roller but not beyond it, and the cut away portion of one of the lugs 9 and the inside link 23, being disposed between the roller and the shouldered member 32. The plate 31 therefore constitutes a runway for the rollers 25. Secured to the support 31 is a guide 34, with an overhanging slot 35, in which the projections 28 of the bolt heads 27 engage, so that as the chain is moved on the support 31, it rides freely on its rollers and the heads of the bolts engage the guide 34 and prevent the dislocation of the chain with respect to the support, even though the chain were depending from the support. The cut away portion at the lower inside edge of the chain permits the wear between the roller and the support to be taken up, the engagement of the head of the bolt with the groove 35 being such that a considerable take up of wear is possible without the disengagement thereof.

With this construction it is obvious that the bits may be removed or inserted with ease, it being necessary only to insert the end of a tool 17, as shown in Fig. 1, below the hook of the locking key, and to draw the key outwardly against the tension of the spring 21, whereupon the bit will be free of engagement therewith and may be inserted or removed with perfect ease. This structure for holding the cutting tools in place in a cutter chain of this type is covered broadly in my co-pending application Ser. No. 860,371, filed September 5, 1914, for cutting chains for mining machines.

It should be particularly noted that the feeding direction of the chain cutter is in-

dicated in Fig. 1 by the arrow 39 and in Fig. 4 by the arrow 39'. Obviously the driving sprocket for the chain is in a plane located substantially at right angles to this direction of feed and intermediate the path of travel of the cutters and the chain guiding mechanism. The path of travel of the cutters is parallel to the path of travel of the heads 27 and projections 28, and such paths of travel are determined by the position or location of the guiding mechanism comprising the shouldered member 32 and the guide 34. It will thus be seen that the structure herein disclosed is particularly adapted for use in mining machines having a loop chain core cutting mechanism with an unobstructed core opening therethrough, such as disclosed in my application for mining machines, Ser. No. 848,727, filed July 3, 1914, and allowed January 7, 1919.

It should be particularly observed that the member 32 may constitute a part of a frame having an unobstructed core opening therethrough, so that when it is moved forward for cutting the core of material in its native bed, the thrust will be taken by that portion of the chain opposite to the cutters. By referring to Fig. 4 it will be seen that the thrust will be distributed over the surface 33, the surface between the links 23 and the guide strips 34, and also by the heads 27 and 28 against the inner surfaces of the members 32 and 34. The line of drive is preferably in the plane at right angles to the chain including the bolts 26 along a line 100 passing through the center of the rollers 25 from left to right, as viewed in Fig. 1, or in the plane of the adjoining inner surfaces of the projections 24. The driving element may be a sprocket wheel the teeth of which project into the spaces between the rollers.

The bolt heads 27 being rectangular in shape, as shown in Fig. 2, may easily be kept from turning by providing the lugs 36 extending laterally from the links 23 and engaging one of the end surfaces of the heads 27 in each instance, as shown in Figs. 1 and 2. In this manner when the nuts 29 are securely fastened in position, the guiding projections 28 are firmly held in proper relation to the guide groove 35, as shown in Fig. 4.

The body portion 32 of the frame support for the cutter chain, is provided with a plurality of spaced apart holes to receive the bolts 37 which, when the nuts 38 are in position, as shown in Figs. 1 and 4, hold rigidly together the plate 31, the grooved plate 34 and the body portion 32 of the frame. It will thus be seen that when the parts are assembled, as shown in Fig. 4, the rollers 25 rest on the projections 31, so that as the latter wear to some extent, the space below the right hand portion of the links 23 will allow for such wear. The bolt heads 27 fit 130

loosely in the L-shaped recess in the forward edge of the body portion 32 of the frame support, and if desired the entire thrust on the chain during the cutting operation may 5 be taken by the surface 33, leaving the upper space between the parts 23 and 24 slightly open, as shown in Fig. 4, and also the space around the bolt head 27 and the guide projection 28. So long as the parts 10 are assembled as shown in Fig. 4 the chain is locked to the supporting frame, although movable longitudinally thereof, this will prevent the chain from being tilted off the support and also from being disconnected 15 therefrom when the cutter chain is moved backwardly through a kerf which has been produced thereby.

Obviously those skilled in the art may make various changes in the details and 20 arrangement of parts without departing from the spirit and scope of my invention as defined by the claims hereto appended, and I wish, therefore, not to be restricted to the precise construction herein disclosed.

25 What I claim and desire to have secured by Letters Patent of the United States, is:—

1. The combination with a traveling cutter chain for mining machines, of rollers carried by said chain, a support engaged by 30 said rollers, a slotted guide secured to said support and located back of said chain relative to its direction of feed, and mechanism projecting rearwardly from said chain relative to said direction of feed to engage the 35 slot of the guide to prevent the dislocation of said chain from said support and to guide said chain for a path of travel transversely of the direction of feed for a plane of drive in advance of said slotted guide and trans- 40 versely of such direction of feed.

2. The combination with a cutter chain, of a support for carrying said chain for feeding movement in a direction transverse to the plane of said chain and for driving movement along the forward edge of said support, a guide secured to said support back of the cutter chain relative to the direction of feeding movement, said guide having an undercut slot located back of said chain relative to its feeding direction, and a rearward projection from said chain in position to engage the said slot to prevent dislocation of said chain from said support during movements of said chain including movement thereof directly opposite to the said feeding movement.

3. In a device of the class described, the combination with movable blocks, of links connected therewith, bolts to connect the 60 links together and to the blocks, each having a head with a lateral projection therefrom, and a guide with a groove to engage the lateral projection of the head of the bolt to hold the chain in a predetermined position.

65 4. A cutter chain for mining machine

comprising cutter blocks, connecting links, bolts for connecting the links and blocks together, a guide, and projections from the heads of some of the bolts back of the chain relative to its feeding direction to coact 70 with said guide to hold the chain in position with respect to the guide and prevent the chain from moving away from the guide while permitting free movement along the same.

5. The combination with a cutter chain comprising cutter blocks, links, and bolts for connecting the blocks and links together, of a support upon which said chain is adapted to travel, and a guide secured to said 80 support to coact with the heads of some of the bolts back of the cutter chain relative to its direction of feed to hold the chain in position on said support by holding the chain from movement away from said support and guiding said chain for path of travel transversely of its direction of feed for a plane of drive in advance of said guide, said plane of drive extending transversely of such direction of feed. 85

6. The combination with a cutter chain having opposite faces adapted to engage the driving means, of a plurality of cutters extending from one edge of said chain to one side of the line of drive, a frame for the 95 opposite edge of said chain, an extension from said frame along one of the faces of said chain and intersecting the line of drive, and a connection between that edge of the chain opposite the cutters and the frame to hold the chain in place relatively to said frame while the face of said chain opposite 100 said extension remains free and unobstructed.

7. The combination with a narrow supporting frame adapted to enter a kerf in a mine wall, of a chain cutter the hinges of which extend in the direction of the feed of said cutter, interlocking guide mechanism back of the chain relative to its direction of feed and between said chain and said supporting frame, and a runway extending from said frame to the intermediate portion of the cutter chain. 105

8. The combination with a cutter chain 110 adapted for a plane of drive substantially at right angles to the plane of said chain and to the direction of feed thereof, of a support, interlocking guiding mechanism back of said chain relative to such direction of feed and between said chain and said support and spaced from such plane of drive, a flat plate serving as a runway for the intermediate portion of said chain and extending from said support to a position intersecting said plane of drive, and cutters carried by said chain and extending from that side thereof opposite the said interlocking guiding mechanism. 115

9. The combination with a chain cutter 120

having a plane of drive extending transversely of the direction of feed, the pivot pins of which extend in the direction of the feed of said chain cutter, of a series of rollers mounted on the chain of said chain cutter with the axis of said rollers extending in the direction of feed, a frame, interlocking guiding mechanism between said frame and said chain back of the latter relative to the direction of feed to hold the chain against movement away from said frame while permitting free movement of said chain along said frame during the cutting operation, and a runway extending from said frame and engaged by said rollers.

10. A cutter chain for mining machines comprising cutter blocks having opposite spaced perforated lugs, links having projections adapted to be inserted oppositely in pairs through the perforations of adjacent spaced blocks until the projections abut, the bearing side of the cutter blocks and the links being partially cut away, a roller mounted on each pair of abutting projections and projecting beyond the cut-away surface of the lug and adjacent links, but not beyond the outer lugs, in combination with a support extending over that portion of the chain where the links and lugs have been cut away to support the chain upon the rollers thereof but not extending outwardly beyond the rollers.

11. A cutter chain for mining machines of the loop chain core-cutter type, comprising cutter blocks with opposite spaced perforated lugs, links having projections adapted to be inserted oppositely in pairs through the perforations of adjacent blocks until such projections abut, the bearing side of the links and lugs on one side of the chain being cut away, a roller mounted on each pair of abutting projections and projecting beyond the cut away surface of the lug and the link but not beyond the other lug, combined with guiding mechanism comprising a cutter frame having a reentrant groove therein back of said chain, means projecting rearwardly from said chain for travel along said groove to hold said chain from movement away from said frame, and a support projecting forwardly from said frame relative to the direction of feed in position for engagement by said rollers while said chain is guided along said frame for a plane of drive in advance of said guiding mechanism, such plane of drive extending transversely of the direction of feed.

12. The combination with a chain cutter comprising pivot rods for connecting the chain links, said rods being provided with laterally projecting heads, of means for preventing said heads from turning relatively to said chain, a frame support for said chain, and guiding mechanism between said frame support and said heads.

13. The combination with a cutter chain, comprising bolts at the pivotal portions thereof, means for preventing the heads of the bolts from turning relatively to the links of said chain, a frame for supporting said chain, and guiding mechanism between said frame and the heads of said bolts.

14. The combination with a cutter chain having pivots extending in the direction of feed, of a supporting frame having a body portion with an angular recess in the forward edge thereof back of the chain relative to the direction of feed, a plurality of spaced apart devices connected to one edge of said chain and fitting in said recess, and a grooved member secured to said body portion and coacting with said devices to lock said chain against movement away from said frame while permitting free guiding movement longitudinally thereof for a plane of drive transverse of the direction of feed.

15. The combination with a cutter chain having pivots extending in the direction of feed and a plane of drive extending transversely of such direction of feed, of a supporting frame, a plate secured to said frame, said plate having an inner groove, and means extending from said chain into said groove back of said chain relative to the said direction of feed in position to guide the chain along said frame and said grooved plate.

16. The combination with a cutter chain, of a supporting frame comprising an intermediate body portion, a plate extending from said body portion to serve as a runway for one side of said chain intermediate its forward and rear sides, a series of rollers carried by said chain for movement along said runway, an additional plate secured to said body portion with its outer surface adjacent said chain approximately in the plane of that side of said chain opposite the aforesaid intermediate side, and a plurality of spaced-apart devices extending from the rear side of said chain in position to coact with said additional plate to guide said chain along said body portion on said runway and preventing movement of said chain away from said body portion whereby the thickness of said chain is increased only by the thickness of said runway, said additional plate being secured to said body portion wholly back of the rear edge of said chain.

17. The combination with a cutter chain comprising a series of bolts at the pivotal connections between the links, of means for preventing the heads of the bolts from turning relatively to the links engaged thereby, projections on the heads of said bolts, a frame, and means carried by said frame and having an inner groove coacting with said projections on said heads to provide an

interlocking guide between said chain and said support.

18. The combination with a chain cutter comprising a series of spaced apart bolts, 5 of means for preventing turning of the heads of said bolts relatively to the links engaged thereby, projections on said bolt heads, a frame support having a recess engaged by said bolt heads, and a retaining 10 member secured to said frame support and having a groove for receiving said projections.

19. A mining machine chain cutter comprising a chain having a series of links the 15 pivots of which extend in the direction of the feed of said cutter, and interlocking guiding mechanism for said chain spaced from the plane of drive thereof back of the chain relative to such direction of feed.

20. The combination with a cutting chain 20 having a plane of drive transverse of the direction of feed and having links provided with projections at the rear side of said chain relative to the direction of travel, 25 cutters mounted on the opposite side of said chain for cutting travel longitudinally of the chain and feeding movement in the direction of the pivots of said chain, a cutter head having a flange, and an overhanging 30 portion on said flange to form a groove to engage said projections and confine the same to movement along said groove.

21. In mechanism for cutting narrow kerfs in a mine wall, the combination with 35 a cutter chain having link pivots extending in the direction of the feed, of a supporting frame in alignment with said cutter chain in a plane passing therethrough, said chain having a plane of drive transverse of 40 the direction of feed, and interlocking guiding mechanism between said cutter chain and said supporting frame back of the chain relative to such direction of feed to guide the cutter chain along said frame while preventing disconnection therefrom.

22. A mining machine chain cutter comprising a link structure having a plane of drive transverse to the feeding direction of said cutter, cutting means at one side of 50 said chain, a supporting frame adapted to enter the kerf cut by said chain cutter, and interlocking guiding means at the other side of said chain back of the latter relative to the direction of feed and on said supporting 55 frame to prevent movement of said chain away from said supporting frame in feeding direction but permitting free movement of said chain along said frame in the direction of cutting travel.

23. A mining machine chain cutter comprising a link structure having pivots extending in the direction of the feed of said cutter and having a plane of drive substantially at right angles to said pivots and to 60 the opposite faces of the chain, cutting

mechanism secured to one side of said chain at one side of the plane of drive and spaced therefrom, and guiding means connected to the other side of said chain at the other side of said plane of drive and spaced therefrom and with one of its exposed surfaces substantially in the same plane as the adjacent face of the chain, said guiding means being spaced from said plane of drive at the back of the chain relative to the said 75 direction of feed.

24. A mining machine chain cutter comprising a link structure having pivot pins between links, said pivot pins extending in the direction of the feed of said cutter and transversely of the plane of drive, cutting mechanism secured to one side of said chain at one side of said plane of drive and spaced therefrom, a frame adapted to enter the kerf cut by said cutter, and interlocking 80 guiding mechanism between the other side of said chain and said frame back of the said chain relative to the said direction of feed for guiding the chain along the line of cutting travel and locking said chain 85 against the movement away from said frame in the direction of feed; the line of drive being intermediate the cutting mechanism and said interlocking guiding means in a plane substantially at right angles to the direction of feed.

25. In a loop chain core cutter, the combination with movable blocks, of links connected therewith, pins for pivotally connecting the links and the blocks, cutters mounted 100 on said blocks for feeding movement in the direction of said pivot pins and for cutting travel in a direction transverse to said pivot pins, lateral projections extending from the side of the chain opposite the cutters and 105 rearwardly from the chain relatively to the direction of feed, and a guide with a groove to engage said projections to hold the chain in a predetermined position.

26. A mining machine chain-cutter comprising pivot pins between links of the chain of said cutter, guide heads on said pins, a frame having a guideway for said guide heads, and means for holding said guide heads in a predetermined position relatively to said links to maintain said guide heads in predetermined relation to said guideways.

27. A mining machine chain-cutter comprising pivot pins between the links of the 120 chain of said cutter extending in the direction of the feed of the latter substantially at right angles to the plane of drive, a frame for said chain, guiding mechanism between said chain and said frame and comprising 125 a guideway on said frame and guide heads movable along said guideway and respectively rigidly connected to the inner ends of said pivot pins, and means projecting from the links adjacent said frame for engaging 130

such guide heads to prevent their turning relatively to said links and to hold said guide heads in predetermined position for free movement along said guideway.

28. A mining machine chain-cutter comprising pivot bolts between the links of the chain of said cutter, said bolts having nuts at their outer ends and heads at their inner ends, a frame for said chain, means on said frame to serve as a guideway for said chain, an interlocking connection between said frame and said chain to prevent the latter from moving away from said frame while permitting free movement along the same, such interlocking connection comprising projections from said heads, and projections on the links adjacent the frame for engaging the heads of said bolts to prevent their turning and to hold all of the projections from the heads of said bolts in predetermined positions for effecting the interlocking connection between said frame and said chain.

29. In a chain cutter for loop chain core-cutting mining machines, the combination with a plurality of cutter links having sockets extending into the same from the forward edge thereof, of cutters extending into said sockets, guiding devices extending from the rear side of said cutter links, a guide frame in series with said links and cutters in the direction of feed, means for

locking said guiding devices to said guide frame all along the latter to confine said guiding devices to a predetermined path of movement relative to said guide frame, and intermediate links connected alternately between said cutter links to constitute a chain having a line of drive in a plane approximately at right angles to the direction of feed and intermediate the cutting path of travel and said predetermined path of movement.

30. In chain cutting mechanism for mining machines, the combination with a plurality of links to form a chain, of cutting devices connected to the front side of said chain and extending forwardly therefrom, and means connected to said chain and extending rearwardly therefrom to support said chain for a plane of drive spaced forwardly from said supporting means, such plane of drive being substantially at right angles to the feeding path of travel and parallel to the cutting path of travel of said chain and cutting devices thereon.

In testimony whereof I have signed my name to this specification, in the presence of two subscribing witnesses, on this 1st day of July, A. D. 1914.

EDMUND C. MORGAN.
